UNITED STATES PATENT OFFICE.

WILLIAM J. GROTHUIS, OF CHICAGO, ILLINOIS, ASSIGNOR TO BIFLEX PRODUCTS COMPANY, OF WAUKEGAN, ILLINOIS, A CORPORATION OF DELAWARE.

DESIGN FOR AN AUTOMOBILE BUMPER.

Application filed June 11, 1925. Serial No. 13,742. Term of patent 14 years.

To all whom it may concern:

Be it known that I, WILLIAM J. GROTHUIS, a citizen of the United States, residing at Chicago, in the county of Cook and State of Illinois, have invented a new, original, and ornamental Design for Automobile Bumper, of which the following is a specification, reference being had to the accompanying drawing, forming a part thereof.

The figure is a front view in perspective of the bumper, showing my new design.

I claim:

The ornamental design for an automobile bumper as shown.

WILLIAM J. GROTHUIS.
